(57) **CLAIM**

The ornamental design for an automobile interior rear console, as shown and described.

DESCRIPTION

FIG. 1 is a front perspective view of an automobile interior rear console showing our new design;

FIG. 2 is a perspective view thereof;

FIG. 3 is a front view thereof;

FIG. 4 is a rear view thereof;

FIG. 5 is a side view thereof;

FIG. 6 is an opposite side view thereof; and,

FIG. 7 is a top plan view thereof.

It will be understood that the broken lines shown in the drawings illustrate portions of the automobile interior rear console that form no part of the claimed design.
